Patented Aug. 29, 1916.

UNITED STATES PATENT OFFICE.

DAVID HEYMAN AND THOMAS RAYMOND ARDEN, OF NEW YORK, N. Y., ASSIGNORS TO
M. GROPPER & SONS, A COPARTNERSHIP CONSISTING OF HARRY GROPPER AND
ABRAHAM S. GROPPER, OF NEW YORK, N. Y.

POP-GUN.

1,196,235.

Specification of Letters Patent. Patented Aug. 29, 1916.

Application filed November 23, 1915. Serial No. 62,943.

To all whom it may concern:

Be it known that we, DAVID HEYMAN and THOMAS RAYMOND ARDEN, citizens of the United States of America, residing at New York city, in the county and State of New York, have invented certain new and useful Improvements in Pop-Guns, of which the following is a specification.

Our invention relates to improvements in pop guns, and the type of gun to which the invention is particularly applicable is that in which the gun mouth is provided with a movable cap serving the double purpose of limiting the discharge of an object from the gun, and assisting in inserting such object in the gun mouth, in readiness for another discharge.

The invention consists in novel mechanism for actuating the cap which controls the movement of the object, such as a cork, to be discharged from the gun.

The preferred form of the invention is illustratively exemplified in the accompanying drawing, in which—

Figure 1 is a side elevational view, partly in section, of a pop gun constructed according to our invention; and Fig. 2 is a fragmentary top plan view thereof.

Referring to the drawing by reference characters, 10 denotes the gun stock, and 11 the gun barrel, these parts being secured together and held relatively immovable by the rivets 12.

Adapted to reciprocate within the barrel 11 is a piston 13 against which one end of a coiled tension spring 14 acts, the other end of the spring abutting against a pin 15 which traverses the barrel. Extending rearwardly from the piston 13 in the barrel 11 is a rod 16, having a hooked end 16^a designed to be engaged by a sear 17, pivotally supported at 18 near the rear end of the barrel and adjacent to the stock. The rear end of the sear 17 is normally depressed, by a spring 19, into engagement with the upper surface of a trigger 20 which is pivotally supported at 21 in the barrel extension 11^a.

Slidably supported over the mouth of the gun is a cap 22 preferably provided with slots 23. The rear edge of the cap has perforated, oppositely disposed, ears 24 into which the hooked ends of rods 25 are adapted to engage. These rods are connected near

their rear ends by a pair of cross rods 26 which pass through elongated slots 27 formed in the sides of the barrel 11. The cross rods support a rectangular yoke which comprises the horizontal plate 28 and the vertical plates 29 and 30, the said vertical plates depending within the barrel 11 and into the barrel extension 11^a.

Pivoted at 31 to the barrel extension 11^a is the operating lever which comprises the nose 31^a, the intermediate curved portion 31^b to accommodate the trigger 20, and the hand hold 31^c designed to rest against the gun stock. 32 denotes the cork which is to be discharged from, and reinserted in, the mouth of the barrel 11.

At the rear of the barrel extension 11^a are parallel depending portions 11^b which are indented at 11^c, and the arched portion of the operating lever between the portions 31^b and 31^c is provided with a transverse hole (not shown) into which the indentations 11^c project, when the operating lever is completely retracted. This arrangement prevents accidental movement of the operating lever.

The operation of the device is as follows:—To cock the gun, or place it in position for discharge of the cork 32, the hand hold 31^c is moved away from the gun stock toward the front of the barrel. As a result of this movement, the nose 31^a of the operating lever will be moved toward the rear of the barrel, engaging the plate 30 and the hooked end 16^a of the rod 16. The continued rearward movement of the parts 30 and 16^a results in the cap 22 being moved backwardly (by means of rods 25) until the cork 32 is inserted in the mouth of the gun barrel, and in the hooked end 16^a being engaged by the sear 17. The piston 13 is thus drawn back in the barrel and the spring 16 compressed between the pin 15 and the rear face of the piston. When the hook 16^a and sear 17 are in engagement, which is readily determined by the operator feeling no appreciable resistance to the forward movement of the operating lever, the latter is moved back into initial position so that the hand hold 31^c again rests against the gun stock. The backward movement of the hand hold 31^c is accompanied by forward movement of the nose 31^a of the operating lever, said nose en-

gaging the plate 29 thus moving the cap 22, through the intermediary of the rods 25, forward on the gun barrel. The several parts then occupy the positions indicated in 5 Fig. 1. To discharge the cork from the gun, the trigger 20 is pressed, whereby the sear 17 is rocked about its pivot, releasing the hook 16^a and enabling the spring 14 to distend and force the piston 13 forward in 10 the barrel against the cork 32 and discharge the same. Obviously the cork cannot fly away from the barrel, as the extent of its flight or discharge is limited by the cap 22. The discharge of the cork from the barrel is 15 accompanied by a noise or "pop" as is common to this class of guns.

What we claim as new and desire to secure by Letters Patent is:—

1. In a pop gun, the combination of a 20 stock and barrel, a plug adapted to fit in the barrel mouth, means for discharging the plug from the barrel mouth, a cap slidably mounted at the forward end of the gun barrel and adapted to reinsert the plug in the barrel mouth after discharge of said plug, rearwardly extending rods engaging said cap, oppositely disposed plates connecting the rear ends of said rods, and an operating lever having means to engage said

plates and move said cap backward and forward on the gun barrel. 30

2. In a pop gun, the combination of a gun barrel provided with oppositely disposed slots, a cap mounted at the forward end of said barrel, parallel rods extending rearwardly from said cap, means passing through the slots in the gun barrel and connecting the ends of said rods, and an operating lever adapted to engage said means to actuate said cap. 35

3. In a pop gun, the combination of a gun barrel provided with oppositely disposed slots, a cap mounted at the forward end of said barrel, rods removably engaging said cap and extending rearwardly thereof, a 40 connection for the rear ends of said rods passing through said slots, oppositely disposed plates carried by said connection, and an operating lever having means for engaging said plates to move said cap forward or 45 backward on the barrel. 50

In testimony whereof we have affixed our signatures in presence of two witnesses.

DAVID HEYMAN.

THOMAS RAYMOND ARDEN.
